FIG. 1.

FIG. 3.

FIG. 2.

FIG. 4.

Inventor

John A. Morrison

By *Watson E. Coleman*
Attorney

UNITED STATES PATENT OFFICE.

JOHN A. MORRISON, OF SPOKANE, WASHINGTON.

EXIT LIGHT.

Application filed January 24, 1923. Serial No. 614,657.

To all whom it may concern:

Be it known that I, JOHN A. MORRISON, a citizen of the United States, residing at Spokane, in the county of Spokane and State of Washington, have invented certain new and useful Improvements in Exit Lights, of which the following is a specification, reference being had to the accompanying drawings.

10 This invention relates to improvements in exit lights, and an important object of the invention is to provide in an exit light means preventing accidental extinguishing of the light.

15 A further object of the invention is to provide an exit light having main and auxiliary lighting elements, the main lighting element being normally operative and the auxiliary lighting element becoming operative

20 upon failure of the main lighting element.

A still further object of the invention is to provide a device of this character having means not only whereby the exit may be indicated but means whereby the exit in times 25 of necessity, such as upon failure of the illuminating elements of the building of which the exit forms a part, the exit signal is not only illuminated but likewise provides illumination for the exit proper.

20 An additional object of the invention is to provide devices of this character in self contained units and which may be readily installed to replace the ordinary exit lights now in use.

25 These and other objects I attain by the construction and arrangement shown in the accompanying drawings wherein for the purpose of illustration is shown a preferred embodiment of my invention and wherein 40 like reference characters designate like parts throughout.

In the drawings:—

Figure 1 is a front elevation of an exit light constructed in accordance with my invention;

Figure 2 is a vertical sectional view taken therethrough;

Figure 3 is a view showing the same in position at an exit and indicating in dotted lines a remote position for the control switch; and

Figure 4 is a detail sectional view taken through the switch.

Referring now more particularly to the drawings, the numeral 10 designates a casing of any desired conformation having a

lens 11 in one wall thereof preferably colored red after the usual custom followed with such signals, and provided upon its face with the word "Exit" or other identifying characters 12. The casing 10 is provided in that wall thereof adapted to be directed toward the exit with which the signal is used, with an opening having arranged therein a lens 13 backed by a reflector 14 arranged within the casing and having an illuminating element 15 therein. The inner face of the reflector, or that face thereof facing the interior of the casing 10, preferably forms a mounting for a second illuminating element 16, although this illuminating element may be otherwise disposed if so desired. The casing has further mounted therein a third illuminating element 17, a solenoid coil 18 and a battery 19 and is provided upon its exterior with a switch 20, the purpose of which will presently appear.

The solenoid coil 18 is provided with an armature bar 21 which when not acted upon by the coil, acts as a switch point connecting 20 a pair of spaced contacts 22. The switch 20 embodies pairs of contact members 23 and 24. One contact of the pair 23 is electrically connected with one of the contacts 22 and the other of these contacts is connected 25 through the illuminating elements 15 and 16 with one terminal of the battery 19. The other terminal of this battery is connected with the second contact of the pair 23. One contact of the pair 24 is electrically connected with one side of the illuminating circuit 25 of the building in which the exit lamp is to be employed. The other contact thereof is electrically connected through the winding of the solenoid 18 with one terminal of the 30 illuminating element 17, the other terminal of this element being connected with the opposite side of the illuminating circuit 25. The battery 19 may be of any desired type, either storage or dry type, and is preferably 35 accessible for repair, recharging or replacement through a hinged side section formed in the casing 10, as indicated at 26.

In the use of the device, the same is secured in position at the exit and upon operation of the switch 20, the circuit to the illuminating element 17 is completed through the solenoid coil, energizing the same and causing the armature 21 thereof to be withdrawn from engagement with the contacts 22. Simultaneously the circuit of the illuminating elements 15 and 16 is completed

through the switch 20 but being broken by the withdrawal of the armature 21, these elements do not become active. If, however, the illuminating circuit 25 fail for any reason, as for blowing of the fuse plugs of the circuit (not herein shown) or failure of the source of current, the solenoid 18 being deenergized, the armature thereof fails, completing the circuit through the contacts 22 and causing illumination of the elements 15 and 16. By this illumination, the exit proper, designated at E, is illuminated and the exit signal as represented by the red lights 11 and the wording or indicia 12 carried thereby is likewise illuminated. Particular attention is directed to the fact that the switch 20 is employed for controlling both circuits simultaneously. This is necessary due to the fact that if the circuit 25 were separately controlled as regards the lamp 17, negligent persons might possibly operate one switch without operating the other, thereby causing a wastage of the current from the battery 19.

25 It will furthermore be obvious that the construction as hereinbefore set forth is capable of many changes and modifications. For example, the switch 20 may be arranged at a remote point, as suggested by the dotted lines in the diagrammatic figures and as is likewise suggested by dotted lines in these figures, the illuminating elements 15 and 16 instead of being arranged in parallel may be arranged in series and differently positioned within the casing. Such changes being readily possible, I do not limit myself to the specific structure hereinbefore set forth except as hereinafter claimed.

I claim:

40 1. In an exit light, a casing adapted to be attached to a wall adjacent an exit and having an identifying lens in one wall thereof, a lens positioned in that wall of the casing next adjacent the exit, an illuminating element within the casing for illuminating the last named lens, means for directing the rays of the illuminating element through the last named lens, main and auxiliary elements within the casing for illuminating the first named lens, said main illuminating element being normally active and the first named and auxiliary illuminating elements being normally inactive, means operated by failure of the main illuminating element for rendering active said first named and auxiliary illuminating elements, including a circuit for the main illuminating element, an open circuit for the first named and auxiliary illuminating elements, means operating upon failure of the first named circuit for closing the second named circuit, and manually operable means for simultaneously opening both of said circuits.

45 2. In an exit light, a casing adapted to be attached to a wall adjacent an exit and having an identifying lens in one wall thereof, a lens positioned in that wall of the casing next adjacent the exit, an illuminating element within the casing for illuminating the last named lens, means for directing the rays of the illuminating element through the last named lens, main and auxiliary elements within the casing for illuminating the first named lens, said main illuminating element being normally active and the first named and auxiliary illuminating elements being normally inactive, means operated by failure of the main illuminating element for rendering active said first named and auxiliary illuminating elements, including a circuit for the main illuminating element, an open circuit for the first named and auxiliary illuminating elements, means operating upon failure of the first named circuit for closing the second named circuit, and manually operable means for simultaneously opening both of said circuits.

50 3. In an exit light, a casing adapted to be attached to a wall adjacent an exit and having an identifying lens in one wall thereof, a lens positioned in that wall of the casing next adjacent the exit, an illuminating element within the casing for illuminating the last named lens, means for directing the rays of the illuminating element through the last named lens, main and auxiliary elements within the casing for illuminating the first named lens, said main illuminating element being normally active and the first named and auxiliary illuminating elements being normally inactive, and means operated by failure of the main illuminating element for rendering active said first named and auxiliary illuminating elements.

2. In an exit light, a casing adapted to be attached to a wall adjacent an exit and having an identifying lens in one wall thereof, a lens positioned in that wall of the casing next adjacent the exit, an illuminating element within the casing for illuminating the last named lens, means for directing the rays of the illuminating element through the last named lens, main and auxiliary elements within the casing for illuminating the first named lens, said main illuminating element being normally active and the first named and auxiliary illuminating elements being normally inactive, means operated by failure of the main illuminating element for rendering active said first named and auxiliary illuminating elements, including a circuit for the main illuminating element, an open circuit for the first named and auxiliary illuminating elements, and means operating upon failure of the first named circuit for closing the second named circuit.

3. In an exit light, a casing adapted to be attached to a wall adjacent an exit and having an identifying lens in one wall thereof, a lens positioned in that wall of the casing next adjacent the exit, an illuminating element within the casing for illuminating the last named lens, means for directing the rays of the illuminating element through the last named lens, main and auxiliary elements within the casing for illuminating the first named lens, said main illuminating element being normally active and the first named and auxiliary illuminating elements being normally inactive, means operated by failure of the main illuminating element for rendering active said first named and auxiliary illuminating elements, including a circuit for the main illuminating element, an open circuit for the first named and auxiliary illuminating elements, and means operating upon failure of the first named circuit for closing the second named circuit.

4. In combination, an indicator for an objective, a circuit including means for illuminating the indicator alone, an open second circuit including separate means for illuminating the objective and indicator, and means for completing the second circuit upon failure of the first circuit.

In testimony whereof I hereunto affix my signature.

JOHN A. MORRISON.
